(57) **CLAIM**

The ornamental design for a flexible bottle, as shown and described.

DESCRIPTION

FIG. 1 is an oblique view of a first embodiment of the invented bottle.

FIG. 2 is a side view of the embodiment of the invention shown in FIG. 1.

FIG. 3 is a top view of the embodiment of the invention shown in FIG. 1.

FIG. 4 is a bottom view of the embodiment of the invention shown in FIG. 1.

FIG. 5 is an oblique view of a second embodiment of the invented bottle.

FIG. 6 is a side view of the embodiment of the invention shown in FIG. 5.

FIG. 7 is a top view of the embodiment of the invention shown in FIG. 5; and,

FIG. 8 is a bottom view of the embodiment of the invention shown in FIG. 5.

1 Claim, 6 Drawing Sheets
